UNITED STATES PATENT OFFICE

121,295

DESIGN FOR A COAT

Jesse Freed, New York, N. Y.

Application July 8, 1938, Serial No. 78,349

Term of patent 3½ years

To all whom it may concern:

Be it known that I, Jesse Freed, a citizen of the United States, residing in the Borough of Manhattan, city, county, and State of New York, have invented a new, original, and ornamental Design for a Coat, of which the following is a specification, reference being had to the accompanying drawing, forming part thereof.

Fig. 1 is a front elevational perspective view of a coat embodying my design; and

Fig. 2 is a rear elevational perspective view thereof.

The characteristic feature of my design comprises the combination, on the coat disclosed, of the collar member which is circular in cut, is confined to the front of the coat, and has a dished-in appearance resulting from circular tucks extending downwardly from the top of both sides of the collar member.

I claim:

The ornamental design for a coat, as shown and described.

JESSE FREED.
